tion, Woodside, N. Y., a corporation of New
York

Application September 27, 1949, Serial No. 118,086

4 Claims. (Cl. 68-6)

1

This invention relates to the steaming of fabrics in finishing operations and particularly to an improved apparatus permitting the application of dry steam to both sides of the fabric simultaneously.

In finishing fabrics, it is customary to apply steam to the surface of the fabric and then to subject it to a calendering operation. In the case of tubular fabrics, it is necessary first to distend the material by means of a spreader or propeller. Because of the possibility of spotting the fabric with water, it has been necessary heretofore to apply the steam only at the under side of the fabric. The upper layer, which is spaced from the lower by the spreader, does not receive identical treatment, since the amount and temperature of the steam reaching the upper layer are less than the amount and temperature applied to the lower layer. As a result, the lower layer becomes wider and the edges roll or "curl" so that the "wind-up" is poor and the material does not lie properly on the cutting tables. Also, many dyes are affected by the differential steaming, so that the shade may vary in the two layers after finishing. Thus, under some cutting conditions one side of a garment may have a different shade from that of the other side, a result which obviously is not satisfactory and may lead to rejection of the material. Furthermore, the stitch of the material may be altered in the two layers by the effect of the non-uniform application of steam to both layers.

It has not been possible heretofore to apply steam to the upper face of the fabric because, in projecting steam downwardly from the steam pipe, water condensed from the steam is inevitably delivered upon the face of the fabric, causing "water spots". This is especially detrimental in the case of rayons, satins, and other delicate fabrics. The presence of water spots requires re-finishing, with resultant additional expense.

It is the object of the present invention to provide an improved steam chest which permits the application of steam to the upper as well as to the lower surface of the fabric, with assurance that water resulting from condensation of the steam will not reach the fabric. Moreover, the oppositely directed steam jets may be arranged so that the pressure exerted by the steam is neutralized, and no pressure is applied to the fabric in a manner to distort it. Thus both sides or layers of the fabric will receive uniform steam application and the difficulties heretofore encountered are avoided. The invention, though applicable particularly to tubular fabrics, may be

used for the treatment of single layers of fabric with similar results.

Other objects and advantages of the invention will be apparent as it is better understood by reference to the following specification and the accompanying drawing, in which

Fig. 1 is a transverse section through a steam chest embodying the invention;

Fig. 2 is a side elevation thereof;

Fig. 3 is a section on the line 3—3 of Fig. 2;

Fig. 4 is a diagrammatic illustration indicating the application of the device to tubular fabric; and

Fig. 5 is a similar view showing the application of the device to a single layer of fabric.

Referring to the drawing, 5 indicates a steam pipe to which steam may be delivered from any suitable source and under the desired pressure. The pipe has downwardly directed openings 6 and 7 through which the steam escapes. These openings are preferably placed so that their axes form approximately a right angle. As indicated in Fig. 2, the openings 6 are graduated in size from the inlet end of the pipe, becoming smaller toward the closed end so as to maintain a substantially uniform pressure within the steam chest.

The steam chest comprises a channel member 8 having legs 9 with downwardly turned ends 10 which form baffles as hereinafter indicated, and a channel member 11 with legs 12 having upwardly turned ends 13 which are slightly spaced from the legs 9 forming steam slots 14 through which the steam escapes. The channel members 8 and 11 are clamped between end members 15 with suitable packing material 16 to ensure a steam tight joint by nuts 17 on the pipe 5. The end member 15 at the end opposite the inlet is, as shown in Fig. 3, provided with a passage 18 with inlets 19 and 20 communicating with the space between the legs 9 and 12. An outlet 21 is provided to which a drain pipe (not shown) may be connected so that any condensate forming within the steam chest is continuously withdrawn.

In operation of the device, as the steam escapes into the inner chamber, it follows the direction of the arrows past the legs 9 and baffles 10. Any condensate resulting from partial cooling of the steam and expansion thereof will collect on the legs 9 and baffles 10 and will drain back to the bottom of the compartment and escape through the outlet 19. The steam passing into the end compartments will follow the arrows and escapes through the steam slots 14.

3

The pressure of the steam within the outer compartments is higher than that of the steam passing through and escaping from the slots 14, and the upturned ends 13 are thus maintained at a sufficiently high temperature to prevent the formation of droplets of water in the slots 14. Any condensate which may form in the outer chambers drains to the bottom thereof and thence to the outlets 20. Thus, any condensation of droplets of water in the slots 14 and the delivery thereof to the fabric is avoided, a result which could not be accomplished if the steam escaping through the slots was not surrounded by steam at a higher temperature. Consequently, since only dry steam is delivered through the slots 14, it is possible to direct the steam downwardly upon the fabric being treated without danger of water-spotting the fabric.

Referring to Fig. 4 of the drawing, the arrangement of the installation to treat tubular fabric is indicated, two steam chests 22 and 23 being arranged above and beneath tubular fabric 24 which is caused to travel so that it is subjected to the jets of steam extending transversely thereof and directed downwardly and upwardly against the two layers of fabric. It will be noted that the jets are opposed to each other so that the pressure of the steam is neutralized and is not, therefore, exerted on the fabric in a manner such as to distort it. Uniform treatment of both layers of the fabric is assured, since the jets of steam escaping from the chests 22 and 23 are at uniform pressure and temperature. In Fig. 5 of the drawing, a similar installation is illustrated, in which the steam chests 25 and 26 are arranged so as to direct jets of steam downwardly and upwardly on opposite sides of a single layer of fabric 27. As in Fig. 4, the steam chests are opposed to each other so that no pressure is exerted upon the fabric and both sides of the fabric are subjected uniformly to the action of the steam. As hereinbefore indicated, because of the structure of the steam chests, no water can escape with the steam jets to mark the fabric. The method of and apparatus for steaming illustrated in these Figs. 4 and 5 are described and claimed in our copending application Serial No. 257,088, filed November 10, 1951.

The apparatus as described affords a very marked improvement in the steaming of fabrics

during finishing operations, assuring more uniform results than have been possible with apparatus heretofore available.

Various changes may be made in the form and arrangement of the apparatus without departing from the invention or sacrificing the advantages thereof.

We claim.

1. In an apparatus for directing steam upon the surface of a fabric, the combination of a pipe having perforations longitudinally spaced to permit the escape of steam and a housing surrounding the pipe, the housing consisting of end walls, an inner channel member having legs, an outer channel member having legs partially enclosing the inner channel member between the end walls, the legs of the inner channel member having inturned ends forming baffles and the legs of the outer channel member having inturned ends in parallel relation to the legs of the inner channel member forming therewith slots for the escape of steam, and means for withdrawing condensate from the housing.
  2. Apparatus according to claim 1 in which the means for withdrawing condensate from the housing includes means for withdrawing condensate from both the inner channel member and the outer channel member thereof.

3. Apparatus according to claim 1 in which the perforations in the pipe are of progressively smaller diameter from the inlet end of the pipe.
  4. Apparatus according to claim 1 in which the inner channel member is substantially U-shaped.
